William G. E. Flanders
Inventor

By *Geo. P. Kimmel*
Attorney

UNITED STATES PATENT OFFICE.

WILLIAM G. E. FLANDERS, OF BURLINGTON, VERMONT.

HEAD-MIRROR.

1,298,686.

Specification of Letters Patent.

Patented Apr. 1, 1919.

Application filed April 23, 1917. Serial No. 163,915.

To all whom it may concern:

Be it known that I, WILLIAM G. E. FLANDERS, a citizen of the United States, and resident of Burlington, in the county of Chittenden and State of Vermont, have invented 5 certain new and useful Improvements in Head-Mirrors, of which the following is a specification.

The present invention relates to the class 10 of optics, and has particular reference to new and useful improvements in head mirrors adapted to be carried upon the usual head band and properly positioned with respect to an electric or other light so as to reflect the rays thereof upon the particular part of the patient to be examined, but particularly for the examination of the ears, nose and throat.

The primary object of my invention is to 20 provide a device of the character mentioned having a novel lens carrying plate associated therewith permitting the use of the same head mirror with various kinds of work and also permitting the use of the 25 same by different physicians accustomed to using lenses of various strengths.

A still further object of my invention resides in the provision of a device of the character described that is simple in construction, efficient in operation, that is compact and that can be manufactured and placed on the market at a minimum cost.

Other improvements and novel details in the construction and arrangement of the 35 various parts of the head mirror may be brought out more in detail in the description to follow, which, for a clear understanding of the invention, should be considered in connection with the accompanying drawing, 40 forming a part hereof, and wherein is disclosed, for the purpose of illustration, convenient and satisfactory embodiments of the invention. It is to be noted in this connection that minor changes in the construction 45 and arrangement of the various parts may be made without departing from the spirit of the invention or the principle of operation of the various parts.

In the drawings:

50 Figure 1 is a rear elevation of my invention looking toward the back thereof, and

Fig. 2 is a detached perspective view of the same.

55 Referring now more particularly to the drawing, wherein like reference characters designate corresponding parts throughout

the several views thereof, 1 designates the head mirror, the face 2 thereof being concave and provided with a reflecting surface the concavity thereof being varied as desired 60 so as to throw the reflected light rays from any suitable electric light or other source of illumination, at any desired distance from the face 2, it being understood that the mirror 1 is designed to be carried by a band 65 in the usual manner for mounting the device on the head of the physician or other person using the same for examination purposes or the like. The back 3 of the plate is convexed and is provided with an internally 70 threaded sleeve extension or enlargement 4 for a purpose which will hereinafter appear. An aperture 5 is provided concentrically of the disk 1, forming a sighting means. The pitch of the concave portion may be of any 75 degree depending on the focus desired.

A circular lens carrying plate 6 is provided with an opening 7 concentrically thereof which is adapted to be rotatably mounted on the enlargement 4 disposed between the 80 central opening 5 and the edge of the mirror or reflector, the latter of which is employed with any electric or other illuminating lamp, although it is to be understood that the mirror or reflector can be substituted by any 85 other illuminating means, instead of reflecting the rays from the electric or other light, on to the patient. Adjacent the peripheral edge of the circular plate a plurality of openings 8, preferably equidistantly spaced 90 and concentrically arranged are provided and adapted to receive lenses of various degrees of strength. A thumb screw member 9 provided with a threaded end 10 is adapted to retain the circular plate in rigid position 95 relative to the enlargement 4 by means of the shoulder 11 formed on the screw.

In the use of my improved head mirror, the mirror or reflector is attached to the head by a head band in the usual manner, or in 100 any other preferred manner, the concaved or reflecting surface of the mirror being disposed toward the patient so as to reflect rays from a suitable light source on to the object to be viewed by the examiner, the mirror being 105 designed to be adjusted in the proper position through the medium of its connection with the head band, in the customary manner. In each of the openings in the plate, numbered lens members are provided of various strengths. When a certain lens is wanted the thumb screw 9 is loosened and 110

the lens carrying plate turned until the lens desired registers with the opening 5, after which the screw 9 is tightened to retain the same in the desired position and insure 5 against accidental displacement. It is to be noted that the openings in the plate 6 containing lenses are numbered from 1 to 10 inclusive, while the opening designated zero (0), is without a lens, for the use of a person whose vision is normal. Thus, after the mirror has been adjusted to reflect the rays from a suitable light source on to the object to be viewed or examined, or when the light rays from an electric or other illuminating 10 lamp have been cast upon the object to be viewed or examined, the lens carrying plate is turned until the desired lens registers with the opening 5, so that the proper vision is obtained, and in this way a proper and thorough 15 examination is permitted, and the device adapted for use by persons with different visions or in such a manner as to render the object visible in the desired way, as for instance by magnifying it.

Having fully described my invention, what I claim as new and desire to secure by Letters Patent, is:

1. The combination with a light reflector having a peep opening; of a circular plate 30 smaller than said reflector and turnably supported at its axle on the reflector, said plate having a plurality of spaced concentrically arranged openings therethrough adapted to be successively brought into alignment with the opening of the reflector, one of said openings being unobscured and lenses in the remaining openings, of different values.

2. In a head mirror, the combination of a disk adapted to be supported on the head 40 and having an opening in the center thereof, the face of the disk being concaved and pro-

vided with a reflecting surface, a circular plate turnably supported at its axis on the back of the disk and having a plurality of spaced concentrically arranged openings 45 therethrough, said plate being of such relative size with respect to the disk that said openings are brought into successive registration with the center of the disk when the plate is turned, said disk opening forming a 50 peep opening, one of said openings in the plate being unobscured, and lenses in the remaining openings adapted to suit different visions for viewing an object upon which rays are cast by the reflecting surface of the 55 disk from a suitable light source.

3. In a head mirror, the combination with a concavo-convex disk having a reflecting surface on its concaved side and having a central peep opening, said disk comprising 60 the usual head reflector adapted to be supported on the head at the back or convexed side thereof, and having an internally threaded collar between said peep opening and the peripheral edge thereof at the 65 back portion, a circular plate of smaller diameter than the disk and having an opening at the axis thereof adapted to engage said collar for turnably supporting the plate, said plate having spaced concentrically arranged openings therein adapted to align with the central peep opening of the disk when the plate is turned, one of said openings being unobscured and the other openings having lenses mounted therein, and a thumb screw engaged with the screw threads of said collar to retain the circular plate in a desired position on the disk.

In testimony whereof, I affix my signature hereto.

WILLIAM G. E. FLANDERS.
